DESIGN FOR A COMPRESSOR

Wilbur P. Peterson, Independence, Mo.

Application November 25, 1946, Serial No. 135,067

Term of patent 7 years

(Cl. D65—1)

To all whom it may concern:

Be it known that I, Wilbur P. Peterson, a citizen of the United States, residing at Independence, in the county of Jackson and State of Missouri, have invented a new, original, and ornamental Design for a Compressor, of which the following is the specification, reference being had to the accompanying drawing, forming part thereof.

Fig. 1 is a perspective view;
Fig. 2 is a top plan view;
Fig. 3 is a front elevational view;
Fig. 4 is a side elevational view; and
Fig. 5 is a rear elevational view of a compressor showing my new design.

I claim:

The ornamental design for a compressor, substantially as shown.

WILBUR P. PETERSON.
